INVENTOR.

George G. Mevi

BY

C. J. Stockman ATTORNEY.

UNITED STATES PATENT OFFICE

GEORGE G. MEVI, OF NEW YORK, N. Y.

BOOK SUPPORT

Application filed February 9, 1928. Serial No. 253,034.

One of the important purposes of this invention is to provide a book-supporting device having means for detachably fastening it to the back member of a book-cover and which device includes relatively foldable elements capable of lying in compact relation against said back member when not in use as a support for the book.

Another of the important purposes of the invention is to provide a book-supporting device having means for detachably fastening it to the back member of a book-cover and which device comprises relatively foldable elements which, when in their opened relation, will relieve the user of the book from the burden of holding the latter in a standing position at the rearward inclination which renders inspection or reading of the contents of the book most convenient.

Still another of the important purposes of this invention is to provide a book-supporting device which is characterized in that while it has means for detachably fastening it to the back member of the book-cover and requires no substantial change in the construction of the book-cover itself, yet may remain in its attached relation to the book-cover and while so attached will not in any wise interfere with the storage of the book in an upright or in a horizontal position in a book-case or other place of storage and will not require any substantial additional space for such storage and will not interfere with the use of the book in a horizontal position.

Other purposes of the invention will be apparent from the following description of the preferred embodiment thereof illustrated in the accompanying drawings. In said drawings:

Fig. 1 is a perspective view of an opened book of loose-leaf binder nature supported in open position by a device constructed in accordance with this invention.

Fig. 2 is a sectional view longitudinally through the back part of a book and the book supporting device applied thereto, and showing the members of said device in closed relation.

Fig. 3 is a section on the line 3—3 of Fig. 2, on a larger scale.

Fig. 4 is a detail representation showing a book equipped with said device, in open position upon a horizontal support, the book supporting device being closed.

Fig. 5 is a side view on a much larger scale than the preceding figures, showing a part of the rear end of a book and the members of the book supporting device in relative positions they may occupy while the device is being applied to or removed from the book, and

Fig. 6 is a detail perspective view of the book support in partly open position.

The supporting device constituting this invention is preferably but not exclusively applicable to book-covers of loose-leaf binder nature. A desirable form of such cover, illustrated in the accompanying drawings, comprises lids A and A' having their rear longitudinal ends connected with each other by a flexible back member B and having spaced strips C, C' between which the back members 10 of loose leaves D are arranged and detachably secured by appropriate fastening elements which extend through said strips C, C' and members 10. The preferred construction of each fastening element shown in detail in Fig. 3, comprises two telescopically arranged members, one of which has an internally threaded socket 11 and the other an externally threaded stem 12 to screw into said socket. These members extend through appropriate holes formed in the strips C, C' and in the members 10 of the leaves D and have their outer ends provided with heads 13 and 14, respectively, to lie against the outer surfaces of the strips C, C'. The members 10 are flexibly secured to the body portions of the respective leaves D along their forward longitudinal edges to permit the leaves to be turned relatively to said members.

The supporting device comprises two legs, marked F and G, respectively. The leg F lies closely against the outer surface of the back member B of the book-cover. These legs are hingedly connected with each other, as shown at 15, at one end of the device and are so correlated that when the device is in folded condition, shown in Figs. 2 and 3, the leg G will lie closely against the leg F. A

strap H is fastened, preferably permanently, at one of its ends (its upper end in the illustrated embodiment) to the corresponding end of the leg F and is of such length that it 5 will extend thence over the adjacent end of the back member B of the cover and through the space between the inner surface of said back member and the rear edges of the back members 10 of the leaves and thence around 10 the adjacent edge of said back member B and back to the leg F to which latter its corresponding end is detachably secured, preferably by mating fastening elements 16, 16', respectively attached to the leg F and end 15 of the strap H. In practice, it is preferred to form that part of the strap which is to lie within the space between the rear edges of the members 10 of the leaves and the back B of the cover, of stiff material and to provide 20 flexible end extensions or tabs h, h' therefrom to extend over the opposite ends of the back members B, one of said extensions or tabs, as h' being of such length that it will also extend over the corresponding end of the leg F 25 and alongside the inner surface of said leg. The stiff portion of the body is of substantially the same length as the back member B of the book-cover and of a thickness and width which enables it substantially to fill 30 the space between the rear edges of the leaves-members 10 and said member B. It thus serves to give rigidity to the back of the book to which it is attached and in every way forms a most desirable means for effecting a firm 35 and secure, and yet detachable, connection of the leg F to the book.

The supporting device is completed by a brace member I, of suitable construction. The illustrated brace member has its body 10 formed of substantial material with flexible extensions i, i' from its opposite ends. One of these extensions, as i is preferably permanently secured to the leg F, while the other, i', has means or an element of a means, for 15 detachably securing it to the leg G—the illustrated means for this purpose being of glove fastening nature, comprising two mating members 17 and 18, respectively, secured to the leg G and tab i' and adapted to inter-engage 20 when the legs F and G are in their open relation to thereby hold the legs against accidental displacement from their said folded relation. The member 17, which is attached to the leg G, is also adapted to inter-engage 25 a mating fastening element 19 on the leg F, to thereby detachably secure the corresponding ends of said legs to each other when the device is in its folded relation.

60 One, or preferably both, legs are channeled longitudinally as shown, in order to provide space for the reception of the brace I and for the reception of the ends of the strap H and fastening elements when the support is 65 folded, to thereby permit of a most compact

relation of the elements of the support when the latter is folded.

Reference is hereto made to an application for letters patent executed by me of even date herewith and entitled "Binders" embodying 70 certain features which are also embraced in the instant application.

Having thus described the invention, what I believe to be new and desire to secure by Letters Patent, is:—

75 1. A book support comprising a pair of pivotally connected legs, a strap to extend through the space immediately in advance of the back member of a book-cover and means to detachably secure a free end of the strap to 80 one of the legs.

85 2. A book support comprising a pair of supporting legs pivotally connected to lie one upon the other when in closed position and to occupy a diverging relation when in open position, one of said legs having a longitudinal channel in its inner surfaces, a pivoted brace which lies in said channel when the legs are closed upon each other, securing means for the brace, including elements to secure one 90 end of the brace detachably to one of the legs, and means to secure the support detachably to the back member of a book-cover.

95 3. A book support comprising a pair of supporting legs pivotally connected to lie one upon the other when in closed position and to occupy a diverging relation when in open position, said legs having their confronting surfaces formed to provide a longitudinal channel, a brace having a pivotal connection 100 at one end with one of the legs and foldable into said channel when the support is in closed position, and mating fastening members respectively secured to the other leg and free end of the brace and arranged in said channel when the device is folded and to engage each other when the device is open, to thereby hold the legs in book-supporting relation.

105 4. A book support comprising a pair of supporting legs pivotally connected to lie one upon the other when in closed position and to occupy a diverging relation when in open position, said legs having their confronting surfaces formed to provide a longitudinal channel, a pivoted brace foldable into said 110 channel when the support is in closed position, a fastening member secured to one of the legs, and other fastening members, one of which is secured to the other leg and engages with the first mentioned fastening member 115 when the device is closed and the other of which is secured to the free end of the brace and engages with said first mentioned fastening member when the legs are closed.

120 5. A book support comprising a pair of supporting legs pivotally connected to lie one upon the other when in closed position and to extend in a diverging relation when in open position, one of said legs having a longitudinal channel in its inner surface, a pivoted 125

brace arranged to lie in said channel when the legs are in their closed relation, and a strap to extend through the space immediately in advance of the back member of a book-cover and having one of its ends arranged in said channel, and means to secure said end detachably in said channel.

6. A book support comprising a pair of supporting legs pivotally connected to lie one upon the other when in closed position and to extend in a diverging relation when in open position, one of said legs having a longitudinal channel in its inner surface, a pivoted brace arranged to lie in said channel when the legs are in their closed relation, mating fastening members concealed by said channel when the legs are in their closed relation and cooperative to hold the legs releasably in said relation, a fastening member carried by one end of the brace and arranged to engage one of the first mentioned fastening members when the legs are in their opened relation, a strap to extend through the space immediately in advance of the back member of a book-cover and having one of its ends arranged in said channel, and means to secure said end detachably in said channel.

7. A book support comprising a pair of supporting legs pivotally connected to lie one upon the other when in closed position and to extend in a diverging relation when in open position, said legs relatively formed to provide a channel between their confronting surfaces, releasable means to hold the legs in their open relation, and a strap extending from one end of the support and having its other end arranged in said channel and detachably secured, the portion of the strap intermediate its ends being arranged outside the legs and to extend through the space immediately in advance of the back member of a book-cover.

8. A book support comprising a pair of legs pivotally connected to lie one upon the other when in closed position and to extend in a diverging relation when in open position, a strap comprising a substantially rigid body member to extend through the space immediately in advance of the back member of a book-cover and also comprising flexible extensions from the ends of said body member, and means to secure said extensions to the opposite ends of the support, the means at one end being of detachable nature.

9. A book support comprising a pair of legs pivotally connected to lie one upon the other when in closed position and to extend in a diverging relation when in open position, said legs relatively formed to provide a channel between their confronting surfaces, a brace having a pivotal connection at one end to one of the legs and lying in said channel when of legs are in their closed relation, means to secure the other end of the brace releasably to the other leg, a strap comprising a substan-

tially rigid body member to extend through the space immediately in advance of the back member of a book-cover, and also comprising flexible extensions from the ends of said body member, one of said extensions having an end lying against the inner surface of one of the legs and detachably secured thereto, and means to secure the other extension to the corresponding end of the support.

10. A supporting device to lie against and be secured to the back member of a book cover, including, in combination, a pair of pivotally connected legs adapted to be closed one upon the other and to be opened out into a diverging relationship, means to hold them against accidental displacement when they are opened out and means to extend over the edge of the back member of the book cover and into the space between the inner surface of said back member and the rear edges of the leaves of the book and to attach the supporting device to said back member.

11. A book support including a pair of pivotally connected legs and means to project therefrom into the space immediately in advance of the back member of the book cover to attach the book support removably to said back member and to avoid interference with the turning of the leaves of the book.

12. A book cover having side members or lids, a back member to which the rear longitudinal portions of the side members or lids are hingedly secured to open outwardly on opposite sides thereof, and leaves bound between said side members and whose rear edges are spaced from the inner surface of the back member, in combination with a supporting device to lie against the outer surface of the back member and having an element to extend into the space between the inner surface of said back member and the rear edges of the leaves to attach the device to said back member, said device including a pair of legs which may be folded one upon the other or opened out into a diverging relationship and means to hold them in their opened out position.

In testimony whereof I affix my signature.
GEORGE G. MEVI.
